Filed Jan. 17, 1972, Ser. No. 218,656

Term of patent 14 years

Int. Cl. D28—03
U.S. Cl. D86—10 F

FIG. 1 is a perspective view of a nozzle portion for a hair styling brush showing my new design, the broken line disclosure of the handle portion being for illustrative environmental purposes only;

FIG. 2 is a side elevational view opposite that shown in FIG. 1;

FIG. 3 is a bottom plan view thereof;

FIG. 4 is a top plan view thereof;

FIG. 5 is a front elevational view taken along line 5—5 of FIG. 2; and

FIG. 6 is a rear elevational view taken along line 6—6 of FIG. 2.

I claim:

The ornamental design for a nozzle portion for a hair styling brush, as shown and described.
